STENCIL SCREEN CONSTRUCTION

Harry E. Playford and Franklin B. Holliger,
Toledo, Ohio, assignors to Owens-Illinois Glass
Company, a corporation of Ohio

Application June 28, 1938, Serial No. 216,255

4 Claims. (Cl. 101—127)

The present invention relates to stencil screens and more particularly to reticulated stencil screens which are formed of silk to which there is applied a colloid such as gelatin which is sensitized, exposed, and subsequently developed to provide outlines or designs set out in pervious portions, the remainder of the screen being blocked out in impervious portions. Such screens are extensively used as stencils for transferring vitreous enamel compositions or paints to the surfaces of glass and other vitreous or ceramic articles and are used in poster and other stenciling work.

Screens of this type are usually held taut on an open rectangular screen frame formed of wood or other material to which the edges of the screen are glued, stapled or otherwise secured, the whole forming a rectangular box-like structure and the screen forming the bottom thereof. A vitreous enamel composition or paint is placed on the screen and is forced through the pervious portions thereof, usually by the spreading action of a squeegee.

The stencil screen material for screen units of this type is sometimes formed on a base of cotton or other cloth. In poster work and in the stenciling of large areas, screens known as "wash out" or "block out" screens are employed. These screens are formed on a base of organdy, artificial or cheap silk, and invariably are of an inferior nature. When put into service, such screens will operate satisfactorily to apply two or three decorations or designs to the posters or other articles, but soon deteriorate rapidly due to stretching and consequent sagging. Such stretching as a rule occurs in the direction of travel of the squeegee over the surface thereof with the result that the pervious portions of the screen representing the design not only become warped but shift on the surface undergoing decoration and blur the completed design to such an extent that the edges thereof will not withstand close inspection. Frequently the screen, in addition to stretching longitudinally, also stretches transversely with the obvious result that the design is unacceptably misapplied.

Inferior screens of this nature are seldom, if ever, employed for applying vitreous enamel compositions to the surfaces of vitreous or ceramic articles such as tumblers, bottles, jars and the like, which are subsequently baked to drive off the volatile constituents of the enamel. Such use would be entirely futile because a more serious disadvantage than the mere blurring of the design results from shifting of the screen.

Designs which have been properly applied by a stencil screen method are finely divided and possess small closely spaced increments of the vitreous enamel which are relied upon to present a large surface area by means of which rapid driving off of the volatile constituents may occur in the drying oven. Designs which have been blurred by shifting of the screen, however, are not finely divided because the adjacent increments have become merged. When such designs are baked, the volatile matter is not readily driven off and blistering, cracking, peeling and other forms of roughness occur in the finished design.

The industrial requirements for efficient stenciling of vitreous or ceramic articles such as tumblers, bottles and the like are very exacting and demand a stencil screen which will shift neither longitudinally nor transversely and one which will hold its shape indefinitely on the screen frame. The base material or mesh for a satisfactory screen that will remain in use indefinitely has not been found in this country, although various attempts have been made to weave screens from high grade silks. The only satisfactory screen material that has been found for this purpose is a hand woven silk material that is made in Switzerland and which must therefore be imported at a very great cost. This material, unlike any domestic brands or weaves, is an extremely fine full-gauge weave and is possessed of exquisite workmanship. The material, even after prolonged use as a stencil screen, is found not to have stretched and in addition possesses uniform and lasting capillary characteristics among the individual screen interstices.

Swiss silk of this nature is very expensive at present, costing at its source in Switzerland approximately five dollars a square yard. An import duty of 55% on the material and a reasonable profit for the importer raises the price of the material in this country to nearly ten dollars a square yard. Notwithstanding the inducement of a high cost and a high import duty, American craftsmen have been unable to duplicate the material or to perfect a satisfactory substitute therefor, at least not below the cost of the material in this country. However, because of the relatively high cost of this imported silk screen material, efforts have been made to utilize a hand woven material of a special weave and constructed of metal gauze. Results along this line have been encouraging, if expense is a factor not to be considered. The cost of metal

gauze material suitable for stencil screen work is at present in the neighborhood of fifteen dollars a square yard, which, although economical when compared to the use of inferior short-lived screens is not so when it is considered that the imported silk screen material is available.

The high cost of stencil screen material which is acceptable to the glass and ceramics industry for the decoration of vitreous and ceramic articles has given rise to this invention. The principal object thereof is to provide a stencil screen unit (i. e. a stencil screen mounted upon the usual screen frame) in which the amount of stencil screen material required to produce an efficient and long lasting unit is materially reduced without sacrificing efficiency in operation or in the applied designs.

Another object of the invention is to provide such a stencil screen which will allow for greater visibility of the article undergoing decoration therebeneath than will the usual type of screen unit which employs its full quota of screen material.

Yet another object of the invention is to provide a stencil screen including the usual stencil screen frame to which there is attached a thin sheet of flexible but non-distortable and preferably transparent skin or membrane having an opening or "window" therein over which extends a silk screen fragment of a size adequate to effect proper decoration of articles, the fragment having its edges removably secured to the edges of the opening in intimate contact therewith by means of an adhesive of a character which will firmly hold the screen fragment in position, yet which will permit manual removal of the screen fragment for the purpose of substitution of designs.

Other objects of the invention not at this time enumerated, will become apparent as the following description ensues.

In the accompanying drawing:

Fig. 1 is a bottom plan view of a stencil screen unit constructed in accordance with the principles of the present invention;

Fig. 2 is a fragmentary top plan view of the medial portion of the unit; and

Fig. 3 is a sectional view taken substantially along the line 3—3 of Fig. 2.

In the drawing a stencil screen frame 10 of generally rectangular configuration has secured to the lower side thereof by means of staples 11 or equivalent means a thin and preferably transparent skin or membrane 12 having a substantially rectangular opening 13 formed substantially centrally thereof. The membrane 12 may be formed of any suitable material such as sheet rubber, fibre, muslin and a great variety of other cloths, but is preferably formed of transparent Celluloid in sheet form or of a transparent cellulose ester material possessing a substantial degree of strength so that it will resist stretching and warping in use. Such a material has the additional advantage of being relatively inexpensive, its cost being practically negligible in comparison to the cost of silk screen material of the imported variety.

A silk screen fragment 14 which is preferably rectangular and of a size slightly larger than the size of the opening 13 extends across the latter and has its edges secured to the underneath side of the membrane 12 adjacent the edges of the opening 13 by means of a suitable adhesive 15 which, in the case of Celluloid membranes may be cellulose acetate or acetone or other solvent

for the material of the membrane. The fragment 14 is prepared in the usual manner of screen preparation and has an impervious or blocked-out portion 16 and a pervious portion represented by the numeral 7.

5

The unit is used in the usual manner. Because of the fact that the Celluloid membrane 12 is extremely thin and the screen fragment is secured to the underneath side thereof, the squeegee by means of which coloring material is forced through the screen is not disturbed as it passes over the opening nor is there a tendency for the enamel to collect in the crevices where the screen and membrane are joined together.

The nature of the adhesive 15 is such that the screen fragment 14 may manually be peeled from the membrane 12 in the manner indicated in Fig. 1 and a new screen fragment substituted therefor by the application of fresh adhesive to the junction between the membrane and screen.

20

Obviously, therefore, the improved stencil screen unit of the present invention effects a material saving in screen material. This saving has in practice amounted to as much as eighty cents per unit even with relatively small screens 25 of the type employed for decorating tumblers.

Modifications may be resorted to within the spirit and scope of the appended claims.

We claim:

1. A stencil screen unit comprising a screen 30 frame, a membrane extending across the frame and secured thereto, there being an opening in the medial regions of said membrane remote from the frame, and a fragmentary reticulated silk stencil screen of an overall size slightly in excess of the overall size of the opening in the membrane extending across said opening and having its edges secured to the membrane adjacent the edges of said opening.

2. A stencil screen unit comprising a screen 40 frame, a transparent membrane extending across the frame and secured thereto, there being an opening in the medial regions of said membrane remote from the frame, and a fragmentary reticulated silk stencil screen of an overall size 45 slightly in excess of the overall size of the opening in the membrane extending across said opening and having its edges secured to the membrane adjacent the edges of said opening.

3. A stencil screen unit comprising a screen 50 frame, a sheet of transparent Celluloid extending across the frame and secured thereto, there being an opening in the medial regions of said sheet, and a fragmentary impervious reticulated silk screen of an overall size slightly in excess of the 55 overall size of the opening in the sheet extending across the opening and having its edges secured to the underneath side of the sheet adjacent the edges of said opening by means of a solvent for the Celluloid, said screen having a pervious portion therein representing a design through which coloring material is adapted to be forced by the spreading action of a squeegee.

4. A stencil screen unit comprising a rigid open frame, a sheet of Celluloid attached to one face 65 of said frame and extending inwardly from the frame throughout the length and width of the latter, there being an opening in the sheet centrally thereof, and a sheet of silk spanning the opening and overlapping only marginal portions 70 of the Celluloid sheet and secured thereto by means of a solvent for the Celluloid.
